UNITED STATES PATENT OFFICE.

FREDERICK F. INGRAM, OF DETROIT, MICHIGAN.

BAG-LOCK.

SPECIFICATION forming part of Letters Patent No. 437,760, dated October 7, 1890.

Application filed April 5, 1890. Serial No. 346,660. (Model.)

To all whom it may concern:

Be it known I, FREDERICK F. INGRAM, of Detroit, in the county of Wayne and State of Michigan, have invented a new and useful Improvement in Bag-Locks, of which the following is a specification.

My invention relates to bag-locks, and is an improvement on the device patented to me June 18, 1889, by United States Letters Patent No. 405,357.

The objects of my improvements are to avoid raising the locking-spindle in the operation of releasing the catch, to economize space in the direction of the height of the device, to improve the device for preventing the catch from rising with the latching-bolt, and to separate the key and hand locking mechanisms. I attain these objects in the apparatus illustrated in the accompanying drawings, in which—

Figure 1 is a plan view. Fig. 2 is a longitudinal section. Fig. 3 is a section on the line *x x*, Fig. 1. Fig. 4 is a plan view, with the top of the case cut away. Fig. 5 is a plan of the key-post. Fig. 6 is a section of the key-post on the line *y y*, Fig. 5; and Fig. 7 is a section similar to Fig. 2, showing a modified form of the latching-bolt-locking mechanism.

Similar reference-figures refer to similar parts throughout the several views.

1 is a base-plate secured in position on the bag by rivets 2 2.

3 is a case closed at the top and sides and open at the ends and bottom, except as hereinafter specified. The case 3 is secured to the base-plate 1, said base-plate closing the bottom of said case.

4 is a latching-bolt of the length of the case 3 and having its ends bent upward to close the ends of said case.

13 13 13 13 are vertical guides in the case 3, in which the ends of the latching-bolt 4 reciprocate.

14 14 are lugs by which the bolt 4 may be lifted.

The latching-bolt 4 is bent upward at its center, as shown in Fig. 2, to leave a space under it for the shank of the catch. Said bolt is of the width of the inside of the case 3 at its ends, but is cut away on one side at the raised portion of its center, as shown in Figs. 2 and 3.

5 is an aperture of greater length than width formed through the center of the bolt 4, but extending farther upon one side of the center of said bolt than upon the other.

6 is a bell-crank lever pivoted at 10 to the latching-bolt 4 and provided with arms 7 and 8. The key-post 19 is located between the arms 7 and 8.

12 is a stud rising from the end of the arm 8, of sufficient height to fill the space between the lug 22 and the bolt 4 when said bolt is in its lowest position.

9 9 are notches formed in the latching-bolt 4 at the points over which the arm 7 come at the ends of its travel. The arm 7 is made of elastic material, and is provided with a downwardly-extending stud at its ends, which stud is adapted to fit into the notches 9 9.

15 is a spring resting at its ends upon the latching-bolt 4 and at its center against the top of the case.

16 is a spindle passing through the top of the case 3 at its center and pivoted in said case. Longitudinal motion of the spindle 16 is prevented by the head 17 at the outside end and by the lug 18 at the inner end striking against the top of the case 3. The lug 18 is located directly over and is of the same shape as the aperture 5.

19 is a key-post pivoted in the base-plate 1 and in the top of the case 3.

20 is a slot in the key-post 19, and 21 is a slot in the top of the case 3, through which the key passes. The key-post 19 passes through an aperture in the latching-bolt 4.

22 is a circular lug formed around the key-post 19 just below the top of the case 3.

24 is a catch secured in place on the bag by the rivets 25.

26 is an aperture formed through the side of the case 3 to permit the passage of the catch 24.

27 is a shoulder extending from the upper surface of the shank of the catch 24 at that part which comes directly below the lower edge of the side of the case 3 above the aperture 26, when said catch is secured in place, as shown in Fig. 3. The latching-bolt 4 rests upon the base-plate 1, and is pressed downward by the spring 15.

The operation of the above-described device is as follows: The spindle 16 is turned by

means of the head 17 until the lug 18 registers with the aperture 5 in the latching-bolt 4, as shown in Figs. 2 and 3. When the catch 24 is forced into the case 3, the latching-bolt 4 is forced upward by the inclined surface of the hook at its end, the lug 18 extending into the aperture 5. When the hook on the end of the catch 24 has passed by the latching-bolt, said bolt falls, securing the catch in place, as shown in Fig. 3. The catch is released by the operator raising the latching-bolt 4 by means of the lugs 14 14. When the spindle 16 is turned so that the lug 18 does not register with the aperture 5, the latching-bolt 4 is prevented from rising by the lug 18 striking against its upper surface. The head 17 is marked, as by having one of the points longer than the other when in the form shown in the drawings, or by an indentation in its periphery when in a circular form. When said mark comes to a certain point on the case 3, it indicates that the lug 18 is in position to register with the aperture 5.

When the head is of the radiate form shown in the drawings, the index-point is made of sufficient length to extend beyond the edge of the case, so that the position of the head 17 can be readily ascertained by the feeling.

The latching-bolt 4 may be locked by a key in the following manner: The key is inserted in the slot 20 in the key-post 19, its bit passing through a slot 21 in the top of the case. When the key is turned, its bit strikes against the arm 7 of the bell-crank lever, turning said lever and bringing the lug 10 upon the other arm of said bell-crank lever under the circular lug 22 upon the key-post 19, thus preventing the latching-bolt 4 from rising. The lug 10 is thrown from under the lug 22 by the bit of the key striking against the arm 8 of said bell-crank lever. The stud upon the end of the arm 7, extending into the notches 9 9, prevents any accidental displacement of the bell-crank lever. The shoulder 27 prevents the catch 24 from following the latching-bolt 4 when said bolt is raised by striking against the side of the case 3.

A number of modified forms of the key-locking mechanism may be substituted for that shown in Figs. 2 and 4—as, for instance, that shown in Fig. 8—in which the latching-bolt 4 is locked by the downwardly-extending lug 30 being thrown over the elevated central portion of the latching-bolt 4.

Having fully described my invention, what I claim, and desire to secure by Letters Patent, is—

1. In a bag-lock in which the latching-bolt is disengaged from the catch by drawing upon said bolt, the combination of a case, a latching-bolt provided with an aperture 5, a spindle 16, pivoted in said case and extending in a direction parallel to the motion of said latching-bolt and restrained from motion in the direction of its length, a lug 18 upon said

spindle between said latching-bolt and the side of the case toward which the latching-bolt moves when being disengaged from the catch, said lug being adapted to extend into said aperture when turned to register with said aperture and to strike against said bolt and prevent its motion when turned to any other position, and means by which said bolt may be drawn out of engagement with the catch, substantially as shown and described. 75

2. In a bag-lock in which the latching-bolt is disengaged from the catch by drawing upon said bolt, the combination of a case, a latching-bolt provided with an aperture 5 and bent at its ends to form the ends of said case and lugs 14 14, a spindle 16, pivoted in said case and extending in a direction parallel to the motion of said latching-bolt and restrained from motion in the direction of its length, and a lug 18 upon said spindle between said latching-bolt and the side of the case toward which the latching-bolt moves when being disengaged from the catch, said lug being adapted to extend into said aperture when turned to register with said aperture and to strike against said bolt and prevent its motion when turned to any other position, substantially as shown and described. 85

3. In a lock, substantially as described, the combination of a case, a latching-bolt adapted to reciprocate in said case, a key, and a movable piece adapted to be actuated by said key and carrying a lug, said movable piece being arranged so that said lug shall be interposed meditately or directly between said bolt and the side of said case toward which said bolt moves when being withdrawn from engagement with the catch at one end of the travel of said movable piece, substantially as and for the purpose described. 100

4. The combination of a case, a key, a key-post 19, pivoted in said case and extending in a direction parallel to the motion of said latching-bolt and restrained from longitudinal movement, said key-post being provided with a lug 22, and the bell-crank lever pivoted to said latching-bolt and carrying a lug 12 upon one of its arms, the lug 12 being adapted to pass under the lug 22 and lock said latching-bolt at one end of the travel of said bell-crank lever, substantially as shown and described. 110

5. The combination of a case 3, provided with an aperture 26, to permit the passage of the catch, the latching-bolt 4, adapted to reciprocate in said case, and the catch 24, provided with a shoulder 27 at that part of said catch which comes within the aperture 26 when said catch is secured in place, substantially as shown and described. 115
